UNITED STATES PATENT OFFICE.

PHILIP A. MYERS, OF ASHLAND, OHIO, ASSIGNOR TO F. E. MYERS & BRO.,
OF SAME PLACE.

DESIGN FOR A PUMP-BODY.

SPECIFICATION forming part of Design No. 32,966, dated July 17, 1900.

Application filed June 6, 1900. Serial No. 19,328. Term of patent 14 years.

To all whom it may concern:

Be it known that I, PHILIP A. MYERS, a citizen of the United States, residing at Ashland, in the county of Ashland and State of Ohio, 5 have invented and produced a new and original Design for a Pump-Body, of which the following is a specification.

In the accompanying drawings I have shown various views of my new design.

10 Figure 1 is a side elevation. Fig. 2 shows the pump from one end, while Fig. 3 shows it from the opposite end. Fig. 4 shows the side opposite to Fig. 1, while Fig. 5 is a plan view.

15 The base A has flaring walls and is made with open-work to add to its ornamental appearance. Surmounting the base is a cylinder B, which overhangs and extends beyond

the end walls of the base, where it is provided with flanges *a* and at one end a depending 20 projection *b*. Surmounting the cylinder B is a substantially-rectangular part C of an irregular contour along its edges and with an upper surface rounded and curved. Centrally of this part C rises a semicylindrical 25 part E, having each of its sides flattened and having a rounded upper end, as at *c*, the flattened sides being shown at *d*.

What I claim is—

The design for a pump-body as herein shown 30 and described.

PHILIP A. MYERS.
